UNITED STATES PATENT OFFICE.

EDWARD E. BARDSLEY, OF WESTVILLE, NEW JERSEY.

BRACE FOR MUSICAL INSTRUMENTS OF THE BANJO TYPE.

1,206,650.

Specification of Letters Patent.

Patented Nov. 28, 1916.

Application filed June 22, 1916. Serial No. 105,197.

To all whom it may concern:

Be it known that I, EDWARD E. BARDSLEY, a citizen of the United States, residing in Westville, Gloucester county, State of New Jersey, have invented a Brace for Musical Instruments of the Banjo Type, of which the following is a specification.

One object of this invention is to provide a device particularly adapted to instruments of the same general class as the banjo, for permanently maintaining the finger board at a predetermined distance from the strings, the invention including the provision of adjustable means whereby this distance may be varied in order to obtain the best results.

It is further desired to provide a brace for an instrument of the class noted, so arranged as to strengthen and increase the rigidity of the connection between the rim and the neck 20 as well as to increase the rigidity of the rim itself and thereby improve the tone of the instrument.

These objects and other advantageous ends I secure as hereinafter set forth, reference being had to the accompanying drawings, in which,

Figure 1 is an elevation, partly in vertical section, illustrating my invention as applied to a mandolin-banjo; Fig. 2 is a perspective of the main portion of the brace employed in that form of the invention shown in Fig. 1; Fig. 3 is a fragmentary plan of a portion of the device shown in Fig. 1; Fig. 4 is a fragmentary vertical section of an instrument similar to that shown in Fig. 1, illustrating a slightly modified form of the invention; and Fig. 5 is a perspective of the main portion of the brace shown in Fig. 4.

In the above drawings 1 represents the rim of the instrument which is provided with a membranous head 2, a neck 3, strings 4 and a finger board 5 of the well known construction. The rim as usual consists of an annular wooden structure 6 covered with relatively thin sheet metal 7 and held to the base of the neck 3 by any desired means such as screws (not shown). In certain instruments a staff or stem 8 extends diametrically across the rim in continuation of the neck, and in applying my invention to an instrument embodying this construction I provide a tapering bar 9 preferably of metal which at one end is provided with downwardly projecting, substantially parallel arms 10 extending at right angles to its general line and designed to fit on opposite sides of or

straddle the staff 8 at that end thereof adjacent the neck. This same brace bar 9 also has an arm 11 projecting in the opposite direction from the fork formed by the arms 10, for a distance sufficient to bring it above the edge of the rim 1. The opposite end of said bar is provided with outwardly extending lugs 12 designed for the reception of bolts 13 whereby it is connected to a cross piece 14 mounted on the opposite face of the staff 8.

Mounted on the base portion of the neck 3 is an angle piece 15 held thereto by screws as shown and having one of its arms projecting above the edge of the rim 1 immediately adjacent and for the same distance as the arm 11 of the brace 9, there being a bolt 16 whereby these two structures are rigidly though adjustably connected.

In applying my invention to the instrument illustrated, the brace 9 is laid upon the staff 8 with its arms 10 extending on opposite sides of the latter and abutting upon the adjacent inner surface of the wooden ring 6. The angle piece 15 having been attached to the base of the neck 3 as shown, the small end of the brace 9 is rigidly though adjustably connected to the staff 8 by the bolts 13 and the cross bar 14 as shown, and thereafter the bolt 17 is passed through the unthreaded opening in the arm 11 and engaged with the threads in an opening formed in the adjacent arm of the angle piece 15. Said bolt is then set up until owing to the lever action of the brace 9 upon the rim 1, the latter is swung on the neck 3 or is held in any desired position such that the strings 4 are maintained at the desired distance from the finger board 5, as may be ascertained by experiment, sufficient to determine the position in which the tone of the instrument is most satisfactory.

In applying the invention to instruments during their manufacture, the staff 8 may be omitted and the main portion 9^a of my brace be extended completely across the rim and through that portion of the same in line with and most distant from the neck 3, for which purpose its end is threaded and provided with suitable jam nuts 17 and 18, as well as suitable washers. Its opposite end is substantially identical in form with that of the brace 9, being forked in order that it may have a strong yet light portion for engagement with the inner surface of the rim 6. This modified construction has the

advantage of avoiding the necessity for cutting away and therefore weakening the rim in order to allow the staff 8 to pass through it into the neck. In any case the device is 5 adjustable to suit it to instruments of various thickness of rim.

I claim:

1. The combination with a musical instrument having a neck, a rim and strings of a brace extending within said rim and having a projecting arm; a bracket on the neck having an arm projecting adjacent the arm of the brace; and means for connecting said arms.
- 10 2. The combination with a musical instrument having a neck, a rim and strings of a brace extending within said rim and having a projecting arm; a bracket on the neck having an arm projecting adjacent the arm of the brace; and means for adjustably connecting said arms.
- 15 3. The combination with a musical instrument having a neck, a rim and strings of a brace extending within said rim and having arms projecting in opposite directions from one end, one of said arms extending beyond 25 the edge of the rim; a bracket on the neck having an arm extending adjacent said latter arm of the brace; and means for connecting said arms of the brace and bracket.
- 20
- 25
- 30

4. The combination with a musical instrument having a neck, a rim and strings of a brace extending within said rim and having a fork at one end bearing against the inner surface of the rim; an arm projecting from said brace at the same end thereof as said fork; and means for adjustably connecting said arm to the neck.

5. The combination with a musical instrument having a neck, a rim and strings of a brace extending within said rim and having a fork at one end bearing against the inner surface of the rim; an arm projecting from said brace at the same end thereof as said fork; means for adjustably connecting said arm to the neck, the same consisting of an angle piece fixed to the neck; and a bolt extending between the arm of said brace and one of the arms of said angle piece.

6. The combination with a musical instrument having a neck, a rim and strings of a staff extending across said rim; a brace also extending within the rim and forked at one end to engage the latter on either side of the staff; an arm for said brace projecting beyond the edge of the rim; a bracket on the neck having an arm adjacent said arm of the brace; and means for adjustably connecting said arms.

EDWARD E. BARDSLEY.
